(74) *Attorney, Agent, or Firm* — Rutan & Tucker LLP; Hani Z. Sayed

(57) **CLAIM**

The ornamental design for an inverted dome filter, as shown and described.

DESCRIPTION

FIG. 1—Top, front, right side perspective view;

FIG. 2—Bottom, rear, left side perspective view;

FIG. 3—Cross-sectional, front elevation view, the rear, left and right side elevation views being identical, as the device is rotationally symmetric;

FIG. 4—Top plan view;

FIG. 5—Bottom plan view;

FIG. 6—Top, front, right side perspective view of an alternate embodiment (FIGS. 6-10);

FIG. 7—Top, rear, left side perspective view;

FIG. 8—Bottom, front elevation view, the rear, left and right side elevation views being identical, as the device is rotationally symmetric;

FIG. 9—Cross-sectional, back elevation view, the rear, left and right side elevation views being identical, as the device is rotationally symmetric;

FIG. 10—Top plan view;

FIG. 11—Bottom plan view; and,

FIG. 12—Top, front, right side perspective view of an alternate embodiment.

1 Claim, 10 Drawing Sheets
